United States Patent Office

Des. 211,605

Patented July 2, 1968

211,605

REFUSE RECEPTACLE FOR USE WITH A MANHOLE COVER

John W. Tingen, Redwood City, and Robert D. Thompson, San Jose, Calif., assignors to Purex Corporation, Ltd., Lakewood, Calif., a corporation of California

Filed Sept. 27, 1966, Ser. No. 4,056

Term of patent 7 years

(Cl. D49—30)

FIG. 1.

FIG. 2.

FIG. 1 is a top perspective view of a refuse receptacle for use with a manhole cover, embodying our new design; and

FIG. 2 is a bottom perspective view thereof.

The broken line showings on the drawing are for illustrative purposes only.

We claim:

The ornamental design for a refuse receptacle for use with a manhole cover, as shown and described.
